UNITED STATES PATENT OFFICE.

OLIVER D. WARFIELD, OF CHICOPEE FALLS, MASSACHUSETTS.

CALIPERS.

SPECIFICATION forming part of Letters Patent No. 364,067, dated May 31, 1887.

Application filed February 28, 1887. Serial No. 229,137. (No model.)

To all whom it may concern:

Be it known that I, OLIVER D. WARFIELD, of Chicopee Falls, in the county of Hampden and State of Massachusetts, have invented new and useful Improvements in Calipers, of which the following is a specification, reference being had to the annexed drawings, forming a part thereof, in which—

Figure 1 is a side elevation, partly in section, of my improved calipers. Fig. 2 is a partial side elevation of a modified form, and Fig. 3 is a detail perspective view of the spring.

Similar letters of reference indicate corresponding parts in all the views.

15 The object of my invention is to provide calipers without pivotal joints.

My invention consists in a joint for calipers and other similar tools, formed of two rolling surfaces held together by a spring, as herein-20 after more fully described.

The legs A, B of the calipers are provided at their pivotal ends with cylindrical convex surfaces *a*, adapted to roll upon each other as the calipers are opened or closed; and in the 25 outer side of each leg of the calipers is formed a mortise, *b*, for receiving the ends of a circular spring, *C*, provided with tenons *c*, fitted to the mortises *b*. In the leg A is loosely pivoted a threaded rod, *D*, which extends through 30 a sleeve, *d*, pivoted in the mortise in the leg B, the said rod *D* being provided with a milled nut, *E*, which may be turned upon the rod for the purpose of adjusting the calipers.

My improvement may be applied to dividers 35 and similar tools.

In Fig. 2 I have shown a modification in which the convex surfaces *a* are provided with teeth or serrations upon their contact-faces.

When my improved calipers are applied to the work, the spring of the calipers is avoided 40 to a great extent by the contact of the convex surfaces and the rigid ends of the calipers, and all of the advantages of the ordinary spring-calipers are secured by employing the spring *C*.

Having thus fully described my invention, I 45 claim as new and desire to secure by Letters Patent—

1. In calipers and similar tools, legs provided with convex surfaces *a*, and means, substantially as described, for holding the convex 50 surfaces in contact.

2. In calipers and similar tools, the combination of the legs A, B, provided with convex surfaces *a* and mortises *b*, and the spring *C*, provided with tenons *c*, fitted to the mortises, 55 substantially as described.

3. As an improved article of manufacture, calipers formed of the legs A, B, provided with the convex surfaces *a* and mortises *b*, the spring *C*, having tenons *c* fitted to the mortises 60 *b*, the threaded rod *D*, pivoted in one leg of the calipers, the sleeve *d*, pivoted in the other leg, and the adjusting-nut *E*, substantially as described.

OLIVER D. WARFIELD.
